(57) **CLAIM**

The ornamental design for a scent training dog bowl, as shown and described.

DESCRIPTION

FIG. 1 is a top perspective view of a scent training dog bowl with a scent pod attached, showing my new design.

FIG. 2 is a bottom perspective view thereof.

FIG. 3 is a top view thereof.

FIG. 4 is a bottom view thereof.

FIG. 5 is a front view thereof.

FIG. 6 is a rear view thereof.

FIG. 7 is a left side view thereof.

FIG. 8 is a right side view thereof.

FIG. 9 is a top perspective view thereof, but shown with the scent pod removed for completeness of illustration.

FIG. 10 is a bottom perspective view thereof.

FIG. 11 is a top view thereof.

FIG. 12 is a bottom view thereof.

FIG. 13 is a top perspective view of the scent pod, shown removed from the bowl for completeness of illustration.

FIG. 14 is a bottom perspective view thereof.

FIG. 15 is a top view thereof.

FIG. 16 is a bottom view thereof.

FIG. 17 is a front view thereof.

FIG. 18 is a left side view thereof.

FIG. 19 is a right side view thereof.

FIG. 20 is a rear view thereof; and,

FIG. 21 is an exploded perspective view of the scent training dog bowl with scent pod.

The broken lines shown in FIGS. 13, 15 and 21 illustrate environmental structure that forms no part of the claimed design.

1 Claim, 13 Drawing Sheets
